UNITED STATES PATENT OFFICE

2,663,255

MULTICOLOR PROOF PRESS

J Russell Parrish, Des Moines, Iowa, assignor to
 Meredith Publishing Company, Des Moines,
 Iowa, a corporation of Iowa

Application March 3, 1951, Serial No. 213,773

5 Claims. (Cl. 101—174)

1 This invention relates to a multi-color proof press for use in the proofing of curved rotary press plates, although the invention is not necessarily limited to that use. This particular application is a continuation-in-part of application Serial No. 51,400, filed September 27, 1948, now abandoned.

Large rotary presses for printing color sheets may, for example, print hundreds of thousands of the same color sheet on one run. These large presses take considerable time to set up for printing, and this so-called make-ready time may take one hundred or more man hours before the press can be started. This is expensive not only because of the time in labor, but also because the press is not producing during the make-ready time. Furthermore, if there is anything wrong with one or more of the printing plates, it does not show up until a run is started, and thereafter if even a single plate must be removed for correction, the press must be shut down all during the time the correction is made. For the above reasons, proof presses have been devised to test the plates prior to their being disposed on the main press.

The available proof presses also have certain disadvantages. Under present methods of curved plate proofing, a single color proof is pulled by hand of each plate. Usually these are in black ink, so that neither the color may be proofed, nor may the final result in two, three or four colors be seen until the main press is run.

It is therefore an object of the invention to provide an improved multi-color press which may be used as a proof press.

It is also an object of the invention to provide a multi-color proof press in which plate register may be determined prior to sending the plates to the pressroom and prior to attaching them to the main press. Therefore, if certain plates must be cut and leveled, this may be done in advance, thus reducing the make-ready time on the main presses. If necessary to make new plates, they may be ordered when proofed instead of waiting until the run is started.

It is a further object of the invention to provide a multi-color proof press on which the interchangeability of spare plates with regular sets may be checked in advance of press runs, thus saving press time during a run.

It is an additional object of the invention to provide a multi-color proof press in which the results to be obtained from the use of certain inks, the comparative tone intensities for each color and the selection of the proper underlay

may all be checked in advance of placing the plates on the main press.

It is a further object of the invention to provide a multi-color proof press on which perfect register checking may be obtained on a plate proof, since the sheet does not leave the gripper bars of the impression cylinder until all the colors are printed. Furthermore, the wet inking process used on multi-color high speed presses may also be used on a proof, thus obtaining close to true press conditions on a proof press.

It is a further very important object of this invention to provide a multi-color proof press in which the colors are printed in proper sequence, and where the proof is printed as the finished product will be and not reverse.

It is still a further object of this invention to provide a multi-color proof press which is adaptable for continuous operation and small production runs.

It is a further important object of this invention to provide a multi-color proof press having a relatively large size impression cylinder.

With these and other objects in view, my invention consists in the construction, arrangement and combination of the various parts of my device whereby the objects contemplated are attained, as hereinafter more fully set forth, pointed out in my claims and illustrated in the accompanying drawings wherein:

Figure 1 is a diagrammatic view of a multi-color proof press showing the relative position of the plate cylinders and impression cylinder; and also showing shelves over which sheets are delivered to and received from the impression cylinder when this multi-color proof press is used as a job press for continuous operation or small production runs;

Figure 2 is a schematic view of the grippers on the impression cylinder and the actuating mechanism therefor, and is taken looking upwards on Figure 1 from beneath the impression cylinder, with the feeding shelf removed;

Figure 3 is a diagrammatic view of the grippers just seizing a sheet to be printed;

Figure 4 is a diagrammatic view of the grippers just opened and with a printed sheet being discharged from the impression cylinder;

Figure 5 is a diagrammatic view of the tumbler used to open and close the grippers showing the position of the tumbler just before it closes the grippers;

Figure 6 shows the tumbler just after the grippers are closed;

Figure 7 shows the tumbler just before the grippers are opened;

Figure 8 shows the tumbler just after the grippers are opened;

Figure 9 is an enlarged side elevation of the multicolor proof press shown in Figure 1, illustrating a typical automatic operating mechanism and cam arrangement for reciprocating the tumbler actuating pins when this proof press is being used as a job press;

Figure 10 is another view of the operating mechanism for the tumbler actuating pins and is taken on line 10-10 of Figure 9; and

Figure 11 is a detailed drawing of a cam shown in Figure 9.

Referring to the drawings, the following general observations are true with respect to the invention shown therein. The impression surface of an ordinary proof press covers most, if not all, of the surface of the impression cylinder. On the other hand, it will be noted that in my invention the impression surface covers no more than one-half of the impression cylinder surface, and therefore the impression cylinder must be larger relative to ordinary proof press impression cylinders.

A few of the many advantages of having a large size impression cylinder will now be set forth. With a large impression cylinder, there is increased time of contact of the printing plate with the impression surface and this effects better transfer of the ink. This increased time of contact is known as a period of dwell and the results of such increased period are the same as would be attendant with a slower speed of rotation of the impression cylinder. There is also an increased area of contact thus making it easier to control the amount of impression, especially in localized areas. The interface force between the plate cylinder and the impression cylinder may be decreased thus more closely simulating the desired "kiss" impression. A further result of the reduced interface force is a decrease in the wear of the printing plates and vital press parts, also due in part to reduced shock. Furthermore, there is less humping of plates, better matching with engravers' proofs (which are made flat), and a decrease of pull of ink from the plate cylinder.

Furthermore, if the same peripheral speed is maintained there is a decrease in the centrifugal force upon the paper as the rotary speed decreases. The paper also lies better on a larger diameter cylinder and fewer wrinkles result. It will also be evident that larger size impression cylinders provide more accessibility to rollers, plates and packing, with a resultant lower cost of operation and lower maintenance cost.

Still further, small impression cylinders tend to bow as does a loaded beam due to the uneven and uncontrolled interface pressure between the plate cylinders and the impression cylinders. Small diameter cylinders, forced to operate at higher speeds, also have a tendency to whip, especially when used with unbalanced plate cylinders. Both of these undesirable features are obviated by the use of a large size impression cylinder.

Although the exact position of the plate cylinder or cylinders around the impression cylinder is unimportant from the standpoint of many of the principles involved herein, the plate cylinders must be positioned so as not to interfere with the impression cylinder taking on fresh sheets or discharging printed sheets. The positioning of the plate cylinders with respect to the points

where the sheets are picked up and discharged from the impression cylinder is shown in Figure 1. The plate cylinder or cylinders may, however, best be located to suit the convenience of the operators for removing and replacing the plates, for proper inking, and for feeding sheets of paper to the impression cylinder. Since more than one color of ink is to be applied to each plate cylinder, the inking or form rollers may be engaged and disengaged by means of a cam (not shown) on the plate cylinder in a manner well known in the art.

In the design shown in the accompanying drawing, the surface of the plate cylinders are each divided into three equal sized portions or segments. The impression cylinder is divided into two equal sized portions or segments, each of which latter portions are equal in size to the plate cylinder portions. The peripheral speed of all three cylinders is the same. It is therefore obvious that the gearing ratio between the impression cylinder and the plate cylinders is other than 1:1. It will further be noted that the ratio between the impression cylinder diameter and the diameter of the plate cylinders is an aliquant number. In other words, the ratio is such that when the smaller number is divided into the larger number, a fraction is always left over. This provides that the color plates on the plate cylinders successively contact one and the same area on the impression cylinder, whereby a sheet of paper placed on this particular area will receive successive imprints of different colors always in the same predetermined sequence.

It will be recognized that the ratio between the circumference of the impression cylinder and the circumference of the plate cylinder is the same aliquant number as the ratio of the diameter of the impression cylinder and the diameter of the plate cylinder, since the circumference of a cylinder is merely π times the diameter. Since segments of the impression cylinder and plate cylinder must repeatedly coincide in predetermined sequence during a printing run, the circumference may be defined in terms of these segments and a unit of circumferential length will be defined in terms of an impression surface on which the sheet to be printed is mounted, or in terms of a plate surface which carries the ink. This unit of circumferential length is an aliquot part of both the circumference of the impression cylinder and the circumference of the plate cylinder. In this specification, the relationship of impression surfaces to plate surfaces will be taken up and described, as such relationship is simpler than a discussion of the relationship of the diameters of the impression and plate cylinders.

In the normal operation of proof presses, only a few prints are pulled, corrective work is accomplished, and then possibly a few more proofs made. The sheet upon which the proof is printed is usually fed to the impression cylinder by hand over a feed board above the impression cylinder. The grippers are usually operated by means of a foot pedal.

The impression cylinder is then turned the necessary number of times to complete a cycle and complete the printing of the proof. The operator then reaches under the feed board to grasp the lower edge of the printed sheet and then releases the grippers by pressing the foot pedal.

In the description of this invention, it will be noted that the sheet upon which the proof is to be printed is fed to the impression cylinder over

a feed board or shelf below the impression cylinder. When the elements of this invention are used solely as a proof press it makes no difference whether the sheets are fed to the bottom or top of the impression cylinder. But when this invention is used as a job press, it is necessary that the printed sheets be discharged face up so that the ink not be smeared, and, therefore, the sheets are fed to the bottom of the impression cylinder.

In this application the proof press, modified with automatically operating grippers so as to be usable as a job press, will be described. The description of the pedal mechanism for operating the grippers, which pedal mechanism would probably be used when this invention is used only for proofing, will be omitted as it is well known in the art.

Referring now in particular to the drawings, there is shown in Figure 1 a multi-color proof press comprising a single impression cylinder 10 and two plate cylinders 12 and 14. The impression cylinder 10 and plate cylinders 12 and 14 are geared together to rotate at the same peripheral speed. The impression cylinder 10 is of smaller diameter than are the plate cylinders 12 and 14. The ratio of the circumference of each plate cylinder 12 and 14 to the circumference of the impression cylinder 10 is 3:2. The impression cylinder 10 is provided with one impression segment or surface 16 and a single set of grippers 18. The impression surface 16 on impression cylinders 10 extends substantially over one-half of the circumference of cylinder 10. The remaining portion or segment of the circumference of impression cylinder 10 is recessed or undercut at 20. The grippers 18 are mounted within the recessed portion 20 and thus it is not necessary to provide an additional recess space wherein the grippers 18 are mounted.

The plate cylinder 12 is provided with two segments for printing plates 22 and 24, each of which is substantially of the same arcuate length as impression surface 16. An undercut or recessed portion or segment 26 is provided between printing plates 22 and 24 and is also of substantially the same arcuate length as impression surface 16. The plate cylinder 14 is similar to plate cylinder 12 and has two segments for printing plates 28 and 30 thereon, with an undercut or recessed segment or portion 29 therebetween.

Each of the printing plates 22, 24, 28 and 30 is adapted to print a different color ink on a sheet to be printed, which is carried upon impression surface 16. For the purpose of this description, it is assumed that the plate 22 applies the yellow color, plate 24-blue, plate 28-red, and plate 30-black. Inking apparatus is provided for applying ink to the surface of the printing plate and is schematically illustrated at 32, 34, 36 and 38. The manner of applying ink to the printing plates from the inking apparatus 32, 34, 36 and 38 is well known in the art and will not be described herein, as their operation does not form part of the invention.

A pair of shelves 40 and 42 are provided adjacent the impression cylinder 10 as shown in Figure 1. The sheets to be printed 41 are fed along shelf 40 to the point where they are gripped by the grippers 18 and the shelf 42 is positioned where it will receive the sheets that are printed after they are discharged from the impression surface 16 upon the operation of the grippers 18 to an open position.

Referring now more particularly to the grippers, a plurality of the grippers 18 are mounted

on a shaft 44, which shaft is journaled at points 46 and 48, as illustrated in Figure 2. One end of the shaft 44 extends beyond the point where it is journaled, as at 50. This extended end 50 of shaft 44 has a tumbler 52 fixedly mounted thereon. The opening and closing of the grippers 18 is accomplished by arcuately moving the tumbler 52 about the axis of shaft 44, resulting in the arcuate movement of shaft 44, which is fixedly secured to the tumbler 52. Figures 3 and 4, respectively, show the grippers in the closed and open position and indicate the range of arcuate movement of shaft 44 in accomplishing the gripping and releasing of the sheet to be printed.

The tumbler 52 consists of a pair of spaced fingers 54 which form a pocket 56 therebetween, which is located to one side of the point of securement of tumbler 52 to shaft 44, and a second pair of fingers 58 bounding a pocket 60 located diametrically opposite the pocket 56.

When the impression cylinder 10 rotates, the gripper shaft 44 and tumbler 52 rotate with the impression cylinder 10. A pair of tumbler actuating pins 62 and 64 are provided to actuate the tumbler 52 at the proper times to close and open the grippers 18 which pins are best shown in Figures 2, 9 and 10. These actuating pins 62 and 64 are normally withdrawn from the path of the tumbler 52 as it rotates with the impression cylinder 10. At desired intervals these pins 62 and 64 are thrust into the path of tumbler 52 to be engaged by tumbler 52 and to cause the tumblers to operate the grippers 18 to open or closed position.

A portion of the frame of the proof press is designated at 66 and upon this frame the tumbler actuating pins and actuating mechanism therefor are mounted. Referring more specifically to Figures 9 and 10, the pins 62 and 64 are mounted in the frame structure 66 and are normally biased to a withdrawn position, as pin 62 is in Figure 10, as shown in full lines. The position when extended is shown by dotted lines, and is indicated by 62a as shown in Figure 10. The pins 62 and 64 are biased in the withdrawn position by means of springs 68 which are seated in pockets 70 in frame 66. A flange 72 on each pin 62 and 64 cooperates with the spring in a well known manner. The pins 62 and 64 are thrust forward by means of bell cranks 74, which in turn are actuated through push rods 76 which have cam followers 78 at one end thereof rolling over the surface of cams 80 and 82. The bell cranks 74 are pivoted upon pins 75 mounted in ears 75a which project from the frame 66. The push rods 76 are slidingly journaled in blocks 77 which project from frame 66.

The springs 68 serve to maintain the cam followers 78 constantly in engagement with the surfaces of cams 80 and 82. The cams 80 and 82 are mounted on a shaft 84 upon which one of the plate cylinders 12 or 14 is mounted. As shown specifically in Figure 9 the shaft 84 is the shaft upon which plate cylinder 12 is mounted.

The location of tumbler actuating pins 62 and 64 is of great importance, for they must be positioned slightly before the point at which the grippers 18 are closed or opened. It can be seen by referring to Figures 5, 6, 7 and 8, that, for example, in the closing of the grippers 18 shown in Figures 5 and 6, the tumbler 52 engages the pin at a point before bottom dead center, where, theoretically, the grippers are to close on the sheet to be printed. Then, as the tumbler 52 continues to rotate counterclockwise about the center of impression cylinder 10, the pin 62 being fixed causes the tumbler 52 to rotate clockwise about the axis

of the gripper shaft 44, causing the shaft 44 itself to be rotated. The grippers 18 mounted on shaft 44 move in the direction to closing position which is shown in Figure 3.

As shown in Figure 6, the tumbler 52 has just moved to the closed position of grippers 18 and the gripper shaft 44 is just past bottom dead center at that point. Similarly, the pin 64 must be positioned so that the grippers 18 are opened when the gripper shaft 44 moves past top dead center. It should, of course, be realized that if gripping or discharge of the sheet to be printed is to take place at other than bottom dead center or top dead center, such may be provided for by the correct positioning of the tumbler actuating pins.

Operation of the multi-color proof press

In the operation of the multi-color proof press, let us refer to Figure 5 where the tumbler 52 is positioned so that the grippers 18 are open and the pin 62 is thrust forward into the path of the tumbler 52 so as to actuate the tumbler 52 to close the grippers 18. The tumbler 52 is so positioned that the fingers 54 pass over the pin 62, causing the pin 62 to enter the pocket 56. The pin being fixed engages the finger 54 and causes the tumbler 52 to rotate clockwise about the axis of gripper shaft 44 as the tumbler moves past the pin 62 in counterclockwise direction. All the time that the tumbler 52 is moving past the pin 62, the pin 62 is moving deeper into pocket 56. The pin 62 and the gripper shaft 44 are closest to each other when they are located upon a radius through the center of rotation of the impression cylinder 10.

As the tumbler 52 continues its counterclockwise rotation about the axis of the impression cylinder the pin causes the clockwise rotation of the tumbler 52 and the shaft 44 about the axis of shaft 44, thus closing the grippers 18. The pin 62 also serves to position the tumbler so that the fingers 58 point in the direction necessary to grasp tumbler actuating pin 64 when the sheet that is printed is to be discharged. It will be noted that the attitude of the tumbler 52 as it leaves pin 62, as shown in Figure 6, is the same as the attitude of the tumbler 52 when it is just grasping pin 64 as shown in Figure 7, for the purpose of discharging the printed sheet of paper.

After the grippers 18 have seized a sheet to be printed, the sheet will have printed on it the color which is carried by printing plate 22 and thereafter during the first revolution of the impression cylinder, the sheet will also have printed on it the color carried by printing plate 28. As the impression cylinder 10 continues to rotate, the recessed surface 20 will register with the recessed space 26 and then later with the recessed surface 29. Upon the second rotation of the impression cylinder 10, the sheet being printed will engage the printing plate 24 and then engage the printing plate 30. The recessed surface 20 upon the second revolution will register with the printing plate 22 and then the printing plate 28, and thus there will be no transfer of ink from these plates to any surface on the impression cylinder during this second revolution.

During the second revolution, the sheet that is being printed may be discharged from the cylinder, but in the preferred embodiment shown, the sheet is not discharged from the cylinder, as it is desirable that the sheet be maintained in continuous contact with the printing plates without any possibility of slipping therebetween. As the impression cylinder 10 makes a third revolution, the impression surface 16 will first register with

the recessed portion 26 and then with the recessed portion 29, during which time no portion of the sheet 16 will be in engagement with any of the printing plates on the plate cylinders. As the tumbler approaches top dead center of the impression cylinder 10 during the third revolution, the pin 64 is thrust forward and the tumbler 52 engages this pin 64, opening the grippers and discharging the printed sheet from the cylinder onto shelf 42.

The tumbler 52 is moving counterclockwise about the axis of the impression cylinder, and when tumbler 52 engages pin 64, the tumbler 52 is caused to rotate counterclockwise about the axis of shaft 44, thus opening the grippers 18. This counterclockwise movement of tumbler 52 about the axis of shaft 44 is illustrated in Figures 7 and 8, the tumbler moving from the position in Figure 7 to the position in Figure 8.

The tumbler 52 when it leaves pin 64 is in the attitude where the fingers 54 are adapted to seize the pin 62 as shown in Figure 5, whereupon the entire cycle is again gone through. The fact that an entire cycle may be continually repeated permits the use of this proof press as a production press for small runs.

While the impression cylinder 10 is making three revolutions, the plate cylinders 12 and 14 are making two revolutions during a complete printing cycle of the proof press. Since the cams are mounted on the shaft of one of the plate cylinders, namely, plate cylinder 12, the pins 62 and 64 will be thrust forward twice during each complete cycle of the running of the proof press. However, there is no possibility of inadvertent engagement of the tumbler 52 with either of the pins 62 or 64, because while the pins 62 and 64 are thrust forward twice during a cycle, they are in the correct position for actuation of the tumbler 52 only once during each cycle. Upon their being thrust forward the second time during the cycle, tumbler 52 is approximately 180° away from the operating position where the pins are being thrust forward, and thus the pins 62 and 64 will not actuate the tumbler 52.

The tumbler 52 is both opened and closed within approximately 180° of rotation of the impression cylinder. The tumbler is opened just before the end of one cycle and, as it moves from approximately bottom dead center to approximately top dead center, it is actuated by pin 62 for the beginning of the next cycle. Thereafter, the pins do not operate the tumbler until the end of the cycle, when the same procedure is repeated.

The cam as shown in Figure 11, has a portion 86 which maintains the corresponding pin in a fully forward position while the impression cylinder rotates about 30°. The total enlarged portion of the cam is limited so that the pins are not partially thrust forward at any time when they may inadvertently trip the tumbler 52.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. A multi-colored printing press comprising a single rotatable impression cylinder and at least one rotatable plate cylinder each having a plurality of equal segments in the surfaces thereof adapted to register tangentially as the cylinders

are rotated, the peripheral length of the surface of the impression and plate cylinders each being an aliquot multiple of the length of the segment, the peripheral length of said impression cylinder comprising an even number of said segments and that of each plate cylinder including an odd number of said segments, means for rotating said impression and plate cylinders at the same peripheral speed, one-half of the number of said impression cylinder segments and one segment on each plate cylinder being recessed, whereby there is no peripheral contact between the impression cylinder and the plate cylinders when a recessed segment on one cylinder registers with any segment on another cylinder, the remaining segments of each plate cylinder each adapted to carry a printing plate therein, the other one-half of the impression cylinder segments being impression segments adapted to carry thereon sheets to be printed by printing plates on said plate cylinders, the recessed segments and the impression segments on the impression cylinder being arranged in alternate order, the number of segments on the impression cylinder and on the plate cylinders providing that during a full cycle of operation each impression segment registers once with each plate cylinder segment in the same predetermined sequence with said recessed segments on the plate cylinder being the last segments to so register, and means for discharging a sheet from the impression segment after said impression segment has registered with each of the plate cylinder segments, whereby the sheet being discharged is completely free of engagement with any printing plate on the plate cylinder.

2. A multi-colored printing press comprising a single rotatable impression cylinder and at least one rotatable plate cylinder each having a plurality of equal segments in the surfaces thereof adapted to register tangentially as the cylinders are rotated, the peripheral length of the surfaces of the impression and plate cylinders each being an aliquot multiple of the length of the segment, whereby the segments on said plate cylinders have their successive edges in juxtaposition, the peripheral length of said impression cylinder comprising an even number of said segments and that of each plate cylinder including an odd number of said segments, means for rotating said impression and plate cylinders at the same peripheral speed, one-half of the number of said impression cylinder segments and one segment on each plate cylinder being recessed, whereby there is no peripheral contact between the impression cylinder and the plate cylinders when a recessed segment on one cylinder registers with any segment on another cylinder, the remaining segments of each plate cylinder each adapted to carry a printing plate therein, the other one-half of the impression cylinder segments being impression segments adapted to carry thereon sheets to be printed by printing plates on said plate cylinders, the recessed segments and the impression segments on the impression cylinder being arranged in alternate order, the number of segments on the impression cylinder and on the plate cylinders providing that during a full cycle of operation each impression segment registers once with each plate cylinder segment in the same predetermined sequence, means for discharging a sheet from the impression segment when said sheet is disengaged from contact with all of said printing plates, the impression segment carrying said sheet registering with the

recessed plate cylinder segments just before said sheet is discharged, and means for feeding a fresh sheet to be printed onto said vacated impression segment before said impression segment next registers with any other plate segment.

3. A multi-colored printing press comprising a single rotatable impression cylinder and at least one rotatable plate cylinder each having a plurality of equal segments in the surfaces thereof adapted to register tangentially as the cylinders are rotated, the peripheral length of the surface of the impression and plate cylinders each being an aliquot multiple of the length of the segment, the peripheral length of said impression cylinder comprising an even number of said segments and that of each plate cylinder including an odd number of said segments, means for rotating said impression and plate cylinders at the same peripheral speed, one-half of the number of said impression cylinder segments and one segment on each plate cylinder being recessed, whereby there is no peripheral contact between the impression cylinder and the plate cylinders when a recessed segment on one cylinder registers with any segment on another cylinder, the remaining segments of each plate cylinder each adapted to carry a printing plate therein, the other one-half of the impression cylinder segments being impression segments adapted to carry thereon sheets to be printed by printing plates on said plate cylinders, the recessed segments and the impression segments on the impression cylinder being arranged in alternate order, the number of segments on the impression cylinder and on the plate cylinders providing that during a full cycle of operation each impression segment registers once with each plate cylinder segment in the same predetermined sequence with said recessed segments on the plate cylinder being the last segments to so register, means for discharging a sheet from the impression segment after said impression segment has registered with each of the plate cylinder segments, whereby the sheet being discharged is completely free of engagement with any printing plate on the plate cylinder, a feeding station past which each impression segment passes as the impression cylinder rotates, said feeding station being positioned adjacent substantially the lowermost point of said impression cylinder, a discharge station adjacent substantially the uppermost point of said impression cylinder, both said feeding and discharge stations being positioned laterally of one side of a vertical plane through the axis of the impression cylinder, and the points of tangency of the plate cylinders with said impression cylinder being positioned laterally of the opposite side of said vertical plane.

4. A multi-colored printing press comprising a single rotatable impression cylinder and a plurality of rotatable plate cylinders, said plate cylinders each having a plurality of equal segments in the surfaces thereof adapted to register tangentially with a plurality of equal segments in the surface of the impression cylinder as the cylinders are rotated, the peripheral length of the surface of the impression and plate cylinders each being an aliquot multiple of the length of the segment, the peripheral length of the said impression cylinder comprising an even number of said segments and that of each plate cylinder including an odd number of said segments, means for rotating said impression and plate cylinders at the same peripheral speed, one-half of the

number of said impression cylinder segments and one segment on each plate cylinder being recessed, whereby there is no peripheral contact between the impression cylinder and the plate cylinders when a recessed segment on one cylinder registers with any segment on another cylinder, the remaining segments of each plate cylinder each adapted to carry a printing plate therein, the other one-half of the impression cylinder segments being impression segments adapted to carry thereon sheets to be printed by printing plates on said plate cylinders, a feeding station past which each impression cylinder segment passes as the impression cylinder rotates, the impression cylinder segments being so arranged that the recessed segments and the impression segments pass said feeding station in alternate order, the number of segments on the impression cylinder and on the plate cylinders providing that during a full cycle of operation each impression segment registers once with each plate cylinder segment in the same predetermined sequence, the segments on the plate cylinders being so arranged that the recessed segment thereon is the last segment of each plate cylinder to register with the impression segment during a cycle of operation, means for discharging a sheet from the impression segment after said impression segment has registered with each of the plate cylinder segments, whereby when the sheet is being discharged it is completely free of engagement with any printing plate on the plate cylinders, and means for feeding a fresh sheet to be printed onto said vacated impression segment before said impression segment next registers with any other plate segment.

5. A multi-colored printing press comprising a single rotatable impression cylinder and a pair of rotatable plate cylinders, said plate cylinders each having three equal segments in the surfaces thereof adapted to register tangentially with a pair of equal segments in the surfaces of the impression cylinder as the cylinders are rotated, the peripheral length of the surfaces of the impression and plate cylinders each being an aliquot multiple of the length of said segment,

whereby the segments on a cylinder have their successive edges in juxtaposition, means for rotating said impression and plate cylinders at the same peripheral speed, one of said impression cylinder segments and one segment on each plate cylinder being recessed, whereby there is no peripheral contact between the impression cylinder and the plate cylinders when a recessed segment on one cylinder registers with any segment on another cylinder, the remaining segments of each plate cylinder each adapted to carry a printing plate therein, the other impression cylinder segment being an impression segment adapted to carry thereon sheets to be printed by printing plates positioned in the remaining segments of said plate cylinders, the number of segments on the impression cylinder and on the plate cylinders providing that during a full cycle of operation each impression segment registers once with each plate cylinder segment in the same predetermined sequence with said recessed segments on the plate cylinders being the last segments to so register, means for discharging a sheet from the impression segment after said impression segment has registered with each of the plate cylinder segments, whereby when the sheet is being discharged it is completely free of engagement with any printing plate on the plate cylinders, and means for feeding a fresh sheet to be printed onto said vacated impression segment before said impression segment next registers with any other plate segment.

J. RUSSELL PARRISH.
